PROCESS FOR STERILIZING VACUUM
CLEANER DIRT RECEPTACLES

Irwin Stone, New York, N. Y.

No Drawing. Application June 14, 1933,
Serial No. 675,711

3 Claims. (Cl. 21—18)

This invention relates to a process for sterilizing the dirt and dust contained in vacuum cleaner bags and receptacles.

It is well known and realized that the dust and dirt contained in the receptacles of suction cleaners are replete with micro-organisms. Scientific investigations have shown the presence of as many as 45,000,000 organisms per gram of household dust—many being pathogenic. This collection of germ laden dust in the vacuum cleaner is a health hazard at all times and especially when the cleaner is in use or being emptied. The inhalation, by the user, of the microbe laden dust needs no further comment as to its unsanitary nature and its effect on one's health.

The prior art, I am aware, describes devices for introducing into the air stream, while the suction cleaner is in use, the vapors of various aromatic chemicals. The vapors of these materials are introduced into the very rapidly moving air stream. The amount of air passing through the cleaner is so large and the available amount of aromatic chemical so small that a germicidal concentration of vapors is never obtained. The employment of this prior art does no more than pleasantly perfume the air passing through the cleaner giving the user a false sense of security and is thus positively dangerous as the ordinary sanitary precautions are then relaxed. In order to obtain a germicidal concentration of vapors in the air rapidly passing through the vacuum cleaner, it would necessitate the use of huge quantities of chemicals and the user would have to wear a gas mask as concentration necessary to quickly kill the germs would make the air in the room irritating, poisonous or otherwise detrimental to human life.

The object of this invention is to provide a germicidal concentration of chemical vapor at the points, where and when needed, without the wasteful or deceiving process of introducing chemicals into large volumes of rapidly moving air.

I have found that by using certain finely powdered germicides or by combining and thoroughly mixing certain pulverulent antiseptic chemical substances with inert colloidal material I could obtain products which are substantially stable en masse but when highly dispersed decompose to give off germicidal vapors.

As examples of these products the following are typical:

55 1. Finely powdered paraformaldehyde may be

used as is, but I prefer to use a mixture consisting of—

	Parts
Paraformaldehyde	50
Infusorial earth	50 5

The two substances are finely powdered and thoroughly mixed in any of the common types of powder mixers.

	Parts
Iodine	10 25
Air floated talc	75

The iodine is dissolved in a sufficient quantity of chloroform to effect solution. When dissolved the chloroform solution is poured onto the talc and mixed in. With continuous stirring the chloroform is permitted to evaporate thereby depositing on each colloidal particle of talc a film of iodine.

	Parts
Paratoluenesulphonchloramide of sodium	20 40
Colloidal clay	60

The two substances are finely powdered and thoroughly mixed in a powder mixer.

The foregoing products are cited as typical examples and the scope of this patent is not to be confined to these ingredients or proportions.

The mode of use which I have found highly successful is as follows: After the vacuum cleaning is finished a measured quantity of the herein described germicidal material is placed on the floor and is then sucked into the vacuum cleaner in the ordinary manner of use. When the pulverulent material strikes the rapidly rotating fan blades it is broken down into a very fine colloidal dispersion and the moving air carries this finely subdivided powder and deposits and mingles it with the dirt in all parts of the receptacle or bag. The suction is then turned off and the cleaner is then stored until its next use. During this storage period, the germicidal material being in a highly dispersed condition and intimately mixed with the germ laden dust, decomposes into the germicidal vapors right at the point needed and as there is no circulation of air the dust is thoroughly sterilized by long time exposure to these vapors. A minimum of chemical substance is only needed by this process as the chemical vapors are kept concentrated in the enclosed space as there is no circulation of air and diffusion is at a minimum due to the presence of the colloid-like material which tends to seal the pores in the bag or receptacle.

Having thus described my invention what I claim is:

- 5 1. A process for sterilizing the contents of vacuum cleaner dirt receptacles which consists in dispersing among said contents, by the action of the moving air stream, a pulverulent solid, said solid containing a high percentage of a solid germicide having a substantially high vapor pressure so that when it is dispersed it tends to emit 10 germicidal vapors, and is then stopping the moving air stream and allowing said emitted germicidal vapors to act upon said contents.
- 15 2. A process for sterilizing the contents of vacuum cleaner dirt receptacles which consists in dispersing among said contents, by the action of

the moving air stream, a pulverulent solid containing a large percentage of paraformaldehyde, and in then stopping the moving air stream and allowing the germicidal vapors to act upon said contents.

- 5 3. A process for sterilizing the contents of vacuum cleaner dirt receptacles which consists in dispersing among said contents, by the action of the moving air stream, a pulverulent solid comprising approximately 50 parts by weight of paraformaldehyde and 50 parts by weight of infusorial earth, and in then stopping the moving air stream and allowing the germicidal vapors to act upon said contents.

IRWIN STONE. 15
